UNITED STATES PATENT OFFICE.

GEORGE WILLIAM BELL, OF NEW YORK, N. Y., ASSIGNOR TO UNION SPECIAL MACHINE COMPANY, OF CHICAGO, ILLINOIS, A CORPORATION OF ILLINOIS.

THREAD CUTTER FOR SEWING MACHINES.

Application filed September 27, 1924. Serial No. 740,291.

The invention relates to new and useful improvements in thread cutters for sewing machines, and more particularly to a thread cutter for a chain stitch sewing machine which operates to cut the enchain loops between stitched articles.

An object of the invention is to provide a thread cutter which is continuously operated when the machine is running and which is located at the rear side of a flat work support so that the enchain loops between a stitched article and the article being stitched may be directed into the thread cutter by the weight of the stitched article passing off from the work support.

A further object of the invention is to provide a work support or extension thereof which is formed with a guiding slot for directing the enchain thread loops into the thread cutting mechanism.

A still further object of the invention is to provide a machine of the above type wherein the thread cutter is operated continuously during the running of the machine by a connection with the feed rocker which operates the feed dog for moving the articles across the work support.

In the drawings which show by way of illustration one embodiment of the invention—

Figure 1 is a view partly in section longitudinally of the work support and from the rear of the machine and showing the thread cutter in rear elevation;

Fig. 2 is a plan view of the parts beneath the work support, the standard being in section;

Fig. 3 is a sectional view on the line 3—3 of Fig. 1;

Fig. 4 is a plan view of the parts shown in Fig. 3, the presser foot and needle being omitted;

Fig. 5 is a sectional view on the line 5—5 of Fig. 3;

Fig. 6 is a sectional view on the line 6—6 of Fig. 3;

Fig. 7 is a sectional view through the thread cutting members and the support for the stationary member.

The machine to which my invention has been applied is a flat bed machine, that is, a machine having a flat work support. The bed plate is indicated at 1 and the flat work support is indicated at 2. The material is fed across the work support by means of a

feed dog 3, which feed dog is carried by a feed bar 4 pivoted at 5 to a feed rocker 6. This feed rocker 6 is moved back and forth by means of an arm 7 which is connected to a link 8 which in turn is connected to a crank pin carried on the end of the main shaft 9. The feed bar is raised and lowered by an eccentric 10 mounted on the main shaft 9. These parts are of the usual construction, and further description thereof is not thought necessary. The feed rocker 6 is mounted at its lower end on a short supporting shaft 11 which is mounted in bearings 12 and 13 at the rear side of the bed of the machine. The feed rocker is rigidly secured to this shaft by means of set screws 14 and 15 (see Figures 5 and 6). The feed bar is secured to a pin 16 mounted in the upper end of the feed rocker 6.

The material is held on the work support by means of a presser foot 17, and the material as it is fed across the work support is stitched by means of a needle 18 and a cooperating looper 19 (see Figures 2 and 3). This looper is of the usual construction and forms a double locked chain stitch. Such a stitching mechanism will form a series of enchain thread loops extending from one stitched article to another.

The machine is particularly adapted for stitching material to form bags. The bags are fed through underneath the presser foot by means of the feed dog, one after another, and the bags are stitched up, and a connected line of enchain loops joins the stitched articles.

The purpose of the present invention is to provide a thread cutter for automatically severing the enchain threads between stitched articles. This thread cutter includes a movable blade 20 and a stationary blade 21. The stationary blade 21 is mounted on a bracket 22 secured to the bed 2 of the machine at the rear side thereof, and projects rearwardly to a point in rear of the feed rocker 6. This bracket 22 has an upwardly extending standard 23 which is formed with a slot 24 in which the stationary member 21 is located. A yoke bracket 25 is secured to this standard 23 and the movable member 20 is mounted in a swinging arm 26 which is rigidly connected to a fulcrum pin 27. This fulcrum pin is located in the yoke bracket 25. A spring 28 surrounding the fulcrum pin normally holds the cutting

blades in shearing contact with each other. The swinging arm 26 is provided with a ball stud 29 with which a link 30 is connected. The lower end of this link is in turn connected to a ball stud 31 carried at the outer end of an arm 32 attached to a sleeve 33 which is clamped by means of a screw 34 to the shaft 11 carrying the feed rocker. As the feed rocker moves back and forth, the arm 32 will be raised and lowered, and through the link 30 will oscillate the arm 26. The movable blade 20 is clamped in the upper end of the arm 26 by means of a set screw 35. Thus it is that the feed rocker operates the movable cutting blade to sever the thread laid between the cutting blades. Inasmuch as the arm 32 projects rearwardly from the feed rocker, it is the upward movement of this arm which operates the movable cutting blade, and the upward movement of the arm 32 is caused by the forward movement of the feed rocker. In other words, the cutter is operated to sever a thread when the feed bar is on its idle stroke.

This thread cutter is located directly in rear of the needle. The work support is provided with an extension 36 (see Figures 3 and 4), which is secured by screws 37 to the work support. This extension may be formed integral with the work support. The only thing essential is that the work support shall extend rearwardly so as to cover a thread cutting mechanism which is directly beneath the same. Said extension 36 is provided with a slot 38, the side walls of which are inclined at 39 away from each other toward the rear edge of the extension, and are curved. The purpose of this slot with the curved walls is to direct the thread connecting stitched articles into the path of the cutting members. The cutting members are operated continuously during the running of the machine. A stitched article indicated at S in Fig. 3 passes over the extreme outer edge of the extension 36 and by gravity is caused to swing underneath said plate carrying the thread t which joins this stitched article S to the article S' being stitched into the path of the thread cutters.

From the above it will be apparent that I have provided what is known in the art as

a flat bed machine with means for automatically cutting the thread of enchain loops connecting stitched articles, and the thread is cut on the idle stroke of the feed bar, so that when the articles are fed forward by the active stroke of the feed bar, the cutters are open ready to receive the enchain loops for cutting the same.

While I have shown a connection to the feeding mechanism for operating the movable thread cutter, it will be understood that, from the broad aspect of the invention, this thread cutter may be operated in any desired way from the main shaft of the machine, the essential feature being that the cutter be located at the rear of the flat work support and in the line of feed so that the article as it is fed out of the machine will cause the enchain stitch leading to said article to be moved into the thread cutter.

Having thus described the invention, what I claim as new and desire to secure by Letters Patent, is—

In a chain stitch sewing machine, a flat work support, stitching mechanism, a feeding mechanism, a continuously operating thread cutter located at the rear side of the work support and in the line of feed, said feeding mechanism including a feed rocker located at the rear side of the work support, said thread cutter including a stationary blade and a movable blade located in rear of the feed rocker and beneath the rear edge of the work support, said work support immediately above said thread cutter being slotted so as to permit the thread between stitched articles to pass through the slot and into the range of the thread cutter, said feed rocker having a rearwardly projecting arm, said movable thread cutter having an arm located above the arm on the feed rocker, and a link connecting the arm on the feed rocker to the arm of the movable blade so that the movable blade is moved away from the stationary blade when the feeding mechanism operates to feed the material, thus separating the blades to permit the thread to enter therebetween.

In testimony whereof, I affix my signature.

GEORGE WILLIAM BELL.
